(57) **CLAIM**

The ornamental design for a handle for a lift and slide fenestration, as shown and described.

DESCRIPTION

FIG. 1 is a front perspective view of a handle for a lift and slide fenestration in accordance with our new design.

FIG. 2 is a front elevational view thereof.

FIG. 3 is a top plan view thereof.

FIG. 4 is a front perspective view of the handle for a lift and slide fenestration of FIG. 1, shown in an alternate position.

FIG. 5 is a top plan view thereof.

FIG. 6 is a front perspective view of the handle for a lift and slide fenestration of FIG. 1, shown in a further alternate position; and,

FIG. 7 is a top plan view thereof.

The broken lines shown in the Figures are for the purpose of illustrating unclaimed portions of the article and form no part thereof. The heavy wavy broken lines that appear at the ends of the lift and slide fenestration represent the bounds of the disclosure and form no part of the claimed design.
